FLUID FLOW SURGE DAMPENING SYSTEM
Robert S. Washburn, Beloit, Wis., assignor to Beloit Iron
Works, Beloit, Wis., a corporation of Wisconsin
Filed Feb. 8, 1961, Ser. No. 87,837
7 Claims. (Cl. 138—30)

This invention relates to devices for dampening pressure surges in fluid conduits, and more particularly, devices for absorbing, dampening or minimizing sudden surges or changes in pressure in fluid pipe lines.

Although the instant invention may have use in a number of fields wherein undesirable effects of pressure surges in pipe lines must be overcome, the instant invention is particularly useful in such aspects of the paper making art as the control of pressure surges in stock flow, and the modification of the instant invention specifically described herein is adapted for this use. Dampening or "desurging" devices have been used or suggested by the prior art in many fields, and particularly in relatively high pressure fluid pipe lines wherein sudden pressure surges may cause damage to the equipment. In the case of paper making machines, the fan pump is subject to surging or pulsation and this is undesirable for the reason that stock delivered by the fan pump should be introduced into the head box with a minimum of surging or other irregularity in the flow rate. The "stock" used in paper machines is a suspension of fibers in water, and because of the presence of the fibers (even though in dilute concentrations) the handling of the stock presents a number of problems. Conventional desurging devices are not effective with paper stock because of the presence of the fibers therein which tend to foul up sensitive control devices or other functioning components.

The instant invention provides a surge dampening device which is free from the problems of conventional prior art devices of this type resulting from the presence of fibers in the stock. In addition, the instant invention provides a simple, sturdy, readily assembled and reliable device which effectively controls or dampens pressure surges in a pipe or duct handling fluid under pressure which must be isolated or which contains components which must be isolated from control elements.

It is, therefore, an important object of the instant invention to provide an improved surge dampening device, and more particularly, to provide an improved surge dampening device for the handling of fluids which must be isolated from control components.

It is a further object of the instant invention to provide a surge dampening device for use in a pipe line to minimize surges of pressure therein, said device comprising, in combination, concentric resilient fluid-impervious sleeves adapted to be mounted in said pipe line and to yieldingly respond to sudden surges of pressure therein, the mean pressure in the pipe being subject to gradual variations, a perforated concentric mandrel interposed between said sleeves and isolated from the pipe fluid, and cushioning compartment means encircling said sleeves for exposing the exterior thereof to gas under substantially the mean pipe pressure to dampen such pressure surges.

Other and further objects, features and advantages of the present invention will become apparent from the following disclosure and the drawing attached hereto and made a part hereof.

The surge dampening device of the instant invention 10 shown in the attached drawing (in the form of a sectional view of one-half of the device 10 above the center line CL) is provided with flanges 10a and 10b of conventional design which may be connected to mating flanges in a pipe or other conduit for the flow of fluid (e.g. stock) therethrough.

2

Certain essential functional elements of the device 10 include a first resilient sleeve member 11 mounted in the pipe line and exposed directly to the fluid flowing therethrough in the area 12. The sleeve 11 is a generally cylindrical member formed of resilient solid elastomer, such as rubber or synthetic resinous elastomer and it is adapted to yieldingly respond to sudden surges of pressure in the fluid flowing in the pipe line and conduit region 12. The mean or average pressure of the fluid in the conduit 12 is subject to gradual variations, as well as the sudden surges of excessively high or excessively low pressure deviating from the mean pressure. The left hand flange element 10a has a threaded recess 10e therein which engages the externally threaded portion 13a of a ring 13 10 to mount the same. The ring 13 has a tapered lip 13b receiving one end 11a of the sleeve 11, which has an annular enlargement 11b at the extremity thereof. An annular clamp 14 has interior threads 14a engaging the exterior threaded portion 13a of the ring 13 for clamping 15 the enlarged end portion 11b of the sleeve 11 into sealing engagement with the ring 13. At the opposite end of the assembly 10 another ring 23 is threadedly received and mounted in a recess 23a in the right hand flange portion 10b; and a second annular clamp 24 threadedly engaging 20 the ring 23 sealingly clamps an enlargement 11c 25 at the opposite end of the sleeve 11. Reading from left to right the elements 10a, 13, 11, 23 and 10b form a substantial continuation of the fluid flow conduit 12, which may be used to replace a small section in a conventional fluid flow pipe (not shown).

A second resilient sleeve 31 concentric with the first sleeve 11 encircles the same and is provided with an annular enlargement 31a at one end which is sealingly clamped against the annular clamp 14 by another ring 35 element 33 threadedly engaging exterior threads 14b of the clamp 14. The resilient sleeve 31 is provided at its opposite end with another annular enlargement 31c which in turn is clamped against the annular clamp 24 by a fourth ring 43 threadedly engaging the annular clamp 24 40 at 24b. Seal rings are provided in conventional manner at 25 between the ring 23 and the flange element 10b, at 26 between the ring 43 (the annular clamp 24) and the flange 10b, and at 27 between the ring 33 (the annular clamp 14) and the flange element 10a.

The sleeve 31 is also formed of resilient elastomeric material such as rubber and it may be formed of the same material as the first sleeve 11. The sleeves 31 and 11 are thus mounted and define therebetween an annular chamber A, which retains fluid under pressure. In the chamber A there is a perforated mandrel 50 that is concentric with the sleeves 11 and 31 and encircles the inner sleeve 11. The mandrel 50 is threadedly received at one end in an annular recess 14c in the annular clamp 14 and at the opposite end in an annular recess 24c in the annular clamp 24. The mandrel 50 is preferably formed of a suitable rigid structural material and it may consist of perforate metal, porous ceramic or any rigid septum. As here shown the mandrel 50 is a metal sleeve having a plurality of throttling orifices 51, 51 of predetermined diameter and spacing to effect the friction losses in the fluid in the chamber A passing therethrough and a surge dampening effect which will be described in detail. The nature of the fluid permeable layer or mandrel 50 coupled with the fluid present in the chamber A will determine to a substantial extent the surge dampening effect that is obtained by the use of this portion of the overall assembly 10, by virtue of the friction factors involved (i.e. for such viscous dampening).

The instant mandrel 50 is also adapted for variable porosity or fluid permeability. In the condition shown in the drawing, the size and spacing of the orifices 51

will determine the fluid permeability. The mandrel 50 is, however, provided with a rather narrow annular central recess 50a which extends throughout the perforated area thereof and opens at the right hand end 50b. This annular recess 50a may be maintained substantially empty, or it may be partially or completely filled with a porous sleeve which will effect a different overall porosity for the mandrel 50. As shown at the right hand end 50b primarily for purposes of example, a short porous sleeve 52 may be used to influence the flow of fluid through some or all of the orifices, depending upon the size of the sleeve 52. In the embodiment shown, the sleeve 52 would effect the porosity of only a portion of the mandrel 50, but a sleeve corresponding in design to the sleeve 52 but substantially equivalent in length to the overall annular recess 50a could be used to replace the sleeve 52 and thus effect an entirely different porosity for the overall mandrel 50. The mandrel 50 divides the chamber A into an inner annular chamber 53 and an outer annular chamber 54 between the sleeves 11 and 31.

In assembling the instant device, the annular clamps 14 and 24 are threaded onto opposite ends of the selected perforate mandrel 50, and the sleeves 11 and 31 are slipped over this assembly 14, 50, 24. The rings 13 and 33 are then threaded onto the annular clamp 14 to seal the left hand end so that the sleeves 11 and 31 and the rings 23 and 43 are threaded onto the other annular clamp 24 to seal the opposite ends of the sleeves 11 and 31. Prior to threading the annular clamp 24 onto the mandrel 50, a selection of the type of permeability control sleeves 52 (if one is to be used) is made and the same is inserted in the mandrel 50. After the rings 23 and 43 have been secured to complete the mounting of the sleeves 11 and 31, the chamber A is filled with a fluid, which may be a gas under pressure such as air, but which is preferably a liquid of sufficient viscosity (i.e. having suitable friction factors) to accomplish the desired viscous dampening in the chamber A during operation. The fluid may be fed into the chamber A through a suitable passageway 24d in the annular clamp 24, and the passageway 24d may then be sealed with a plug 24e.

A sudden surge of pressure in the flow conduit 12 finds initial response in the interior sleeve 11 which yields resiliently by moving outwardly. This in turn causes fluid in the inner side 53 of the chamber A to flow through the orifices 51 and the mandrel 50 (with consequent viscous dampening) which results in a somewhat damped surge against the interior of the outer sleeve 31. The outer sleeve 31, in turn, yields in response to this surge.

The exterior wall 31d of the outer sleeve 31, however, defines with a cylindrical housing 60 a cushioning compartment B. The left hand flange element 10a of the device 10 is provided with a hollow section 10c which receives the annular clamp 14 and ring 33, and a secondary flange section 10d extending upwardly therefrom which cooperates with an annular flange 60d on the left hand end of the cylindrical housing 60. The cylindrical housing 60 is mounted via the flange 10d—60d with suitable bolts as at 61 and a seal at 62. At the right hand side of the housing 60, there is also provided an annular lip 60e mounting a seal 63 for engagement with the exterior of the ring 43 to complete the sealing off of the cushioning compartment B. Fluid under pressure is maintained in the cushioning compartment B and this fluid is preferably a gas such as compressed air (although it may be a liquid such as water). In the preferred embodiment, the viscous dampening chamber A contains a liquid such as distilled water, ethylene glycol, oils, or the like which accomplish the desired viscous dampening during flow through the orifices 51; whereas the cushioning chamber B contains a gas under pressure such as air. Air under pressure is fed from a

source S through a control valve V and into an inlet 64 in the cylindrical housing 60, in a conventional arrangement shown diagrammatically. In the preferred embodiment the air pressure in the cushioning compartment B is maintained substantially equivalent to the mean fluid pressure in the conduit 12, via control of the valve V. In this way the sleeves 11 and 31 are maintained in more or less of an equilibrium position in between pressure surges in the flow conduit 12, but during pressure surges, wherein the pressure varies from the mean pressure, movement of the sleeves 11 and 31 is effected. The left hand flange element 10a is provided with a conventional pressure sensing aperture 65, whereby the pressure in the flow conduit 12 is continuously sensed. Preferably the pressure sensing device indicated diagrammatically at 66 does not actually receive liquid from the conduit, but merely senses the pressure thereof via a diaphragm or other suitable means. The pressure signal thus obtained is a compressed air signal in the line 66, which is also provided with capillary passages at 67 (or other conventional means for damping pressure surges by frictional effect or otherwise, while still transmitting the gradual variations in the mean pressure in the conduit 12). The damping system 67 thus permits the transmission of a fluid pressure signal from the flow line 12 via such damping system 67 to the control valve V which signal received by the valve V is directly responsive to variations in the mean pressure in the conduit 12. The control valve V, in turn, controls the fluid pressure in the cushioning compartment B so as to maintain the same substantially equivalent to the mean fluid pressure in the conduit 12 at any given time.

It will be appreciated that the various elements of the system 64, 65, 66, 67 for the control valve V and the compressed air source S are conventional and these components are indicated diagrammatically. The essential function thereof is to maintain the cushioning compartment fluid pressure responsive (and preferably equivalent) to the mean conduit fluid pressure at any given time. This is accomplished by the use of the fluid pressure sensing means 65, 66, 67 connected to the conduit 12 and the control valve V for transmitting to the control valve V responses to variations in the mean pressure and the pipe 12.

In summary, the instant invention comprises a surge dampening device 10 for use in a conduit 12 to dampen sudden surges of fluid pressure therein, the device 10 comprising a member 11 movable in response to such surges interposed between the conduit 12 and a chamber A and subject to the conduit fluid pressure on one side and a chamber fluid pressure on the other side, an element 31 movable in response to pressure surges interposed between the chamber A and a compartment B and subject to the chamber fluid pressure on one side and a compartment fluid pressure on the other side, a fluid permeable layer 50 interposed between said member 11 and said element 31 dividing said chamber A into two enclosures for throttling chamber fluid pressure from one enclosure to the other, and valve means V maintaining the compartment fluid pressure responsive to the mean conduit fluid pressure.

It will be understood that modifications and variations may be effected without departing from the spirit and scope of the novel concepts of the present invention.

I claim as my invention:

1. A surge damping device for use in a conduit to dampen sudden changes of fluid pressure therein, said device comprising, in combination, a fluid-impervious member movable in response to such surges interposed between the conduit and a chamber and directly exposed to fluid flowing in the conduit so as to be subject to the conduit fluid pressure on one side and a chamber fluid pressure on the other side, a fluid-impervious element movable in response to pressure surges interposed be-

tween the chamber and a compartment and subject to the chamber fluid pressure on one side and a compartment fluid pressure on the other side, a fluid-permeable layer having a plurality of throttling orifices interposed between said member and said element dividing said chamber into two enclosures for throttling chamber fluid flow from one enclosure to the other, valve means maintaining the compartment fluid pressure responsive to a damped signal, means sensing the conduit fluid pressure and sending out a signal in response thereto, and means delaying said signal to dampen abrupt variations therein and sending a damped signal to said valve means.

2. A surge dampening device for use in a pipe line to minimize surges of pressure therein, said device comprising, in combination, a first resilient fluid-impervious sleeve member adapted to be mounted in said pipe line directly exposed to fluid flowing therein and to yieldingly respond to sudden surges of pressure therein, the mean pressure in the pipe being subject to gradual variations, a perforated mandrel having a plurality of throttling orifices encircling said first sleeve, a second resilient fluid-impervious sleeve member encircling said mandrel and maintaining said mandrel in a separate body of fluid, cushioning compartment means encircling said second sleeve for maintaining gas under pressure to dampen such pressure surges, control means for maintaining the gas pressure in said compartment substantially equivalent to the mean pressure in the pipe, means sensing the pipe line fluid pressure and sending out a signal in response thereto, and means delaying said signal to dampen abrupt variations therein and sending a damped signal to actuate said control means.

3. A surge dampening device for use in a pipe line to minimize surges of pressure therein, said device comprising, in combination, a first resilient fluid-impervious sleeve member adapted to be mounted in said pipe line to form a continuation thereof directly exposed to fluid flowing therein and to yieldingly respond to sudden surges of pressure therein, the mean pressure in the pipe being subject to gradual variations, a perforated mandrel having a plurality of throttling orifices encircling said first sleeve, a second resilient fluid-impervious sleeve member encircling said mandrel and maintaining said mandrel in a separate body of fluid, whereby such pressure surges effect flow of fluid in said body through said mandrel and yielding response by said second sleeve, cushioning compartment means encircling said second sleeve for maintaining gas under pressure to dampen such pressure surges, a source of gas under pressure, sensing means connected to the pipe line for sending a fluid pressure signal responsive to pressure in the pipe line, reservoir means delaying and damping the fluid pressure signal from said sensing means and sending a damped fluid pressure signal, and a control valve for said source responsive to the damped fluid pressure signal for maintaining the gas pressure in said compartment substantially equivalent to the mean pressure in the pipe.

4. A surge dampening device for use in a pipe line to minimize surges of pressure therein, said device comprising, in combination, a first resilient fluid-impervious sleeve member adapted to be mounted in said pipe line to form a continuation thereof directly exposed to fluid flowing therein and to yieldingly respond to sudden surges of pressure therein, the mean pressure in the pipe being subject to gradual variations, a perforated mandrel encircling said first sleeve and having a plurality of throttling orifices, a second resilient fluid-impervious sleeve member encircling said mandrel and defining with said first sleeve a chamber wherein such pressure surges effect flow of fluid in the chamber through said mandrel and yielding response in said second sleeve, cushioning compartment means encircling said second sleeve for maintaining gas under pressure to dampen such pressure surges, a source of gas under pressure, sensing means con-

nected to the pipe line for sending a fluid pressure signal responsive to pressure in the pipe line, reservoir means delaying and damping the fluid pressure signal from said sensing means and sending a damped fluid pressure signal, and control means connected to said source of gas under pressure and actuated by said damped fluid pressure signal for maintaining the gas pressure in said compartment substantially equivalent to the mean pressure in the pipe line.

5. A surge dampening device for use in a pipe line to minimize surges of pressure therein, said device comprising, in combination, a first resilient fluid-impervious sleeve member adapted to be mounted in said pipe line to form a continuation thereof directly exposed to fluid flowing therein and to yieldingly respond to sudden surges of pressure therein, the mean pressure in the pipe being subject to gradual variations, a perforated mandrel having a plurality of throttling orifices encircling said first sleeve, a second resilient fluid sleeve member encircling said mandrel and defining with said first sleeve a chamber wherein such pressure surges effect flow of fluid in the chamber through said mandrel and yielding response in said second sleeve, cushioning compartment means encircling said second sleeve for maintaining gas under pressure to dampen such pressure surges, a source of gas under pressure for said cushioning compartment, fluid pressure sensing means for connection to said pipe to transmit a response to variations in the mean pressure in the pipe while dampening out response to such pressure surges, a reservoir receiving fluid pressure signals from said fluid pressure sensing means and sending out damped fluid pressure signals and control valve means for said source responsive to the damped fluid pressure signals transmitted by said sensing means via said reservoir for maintaining the gas pressure in said compartment substantially equivalent to the mean pressure in the pipe.
10. 6. A surge dampening device for use in a pipe line to minimize surges of pressure therein, said device comprising, in combination, a first resilient fluid-impervious sleeve member adapted to be mounted in said pipe line to form a continuation thereof directly exposed to fluid flowing therein and to yieldingly respond to sudden surges of pressure therein, the mean pressure in the pipe being subject to gradual variations, a perforated mandrel having a plurality of throttling orifices encircling said first sleeve, a second resilient fluid-impervious sleeve member encircling said mandrel and defining with said first sleeve a chamber wherein such pressure surges effect flow of fluid in the chamber through said mandrel and yielding response in said second sleeve, cushioning compartment means encircling said second sleeve for maintaining gas under pressure to dampen such pressure surges, a source of gas under pressure for said cushioning compartment, fluid pressure sensing means connected to the pipe line for sending a fluid pressure signal responsive to pressure variations in the pipe line, reservoir means delaying and damping the fluid pressure signal from said sensing means and sending a damped fluid pressure signal and valve means in control of said source for communicating gas pressure to said compartment in response to variations in the damped fluid pressure signal for maintaining the gas pressure in said compartment substantially equivalent to the mean pressure in the pipe.
15. 7. A surge dampening device for use in a pipe line to minimize surges of pressure therein, said device comprising, in combination, concentric resilient fluid-impervious sleeves adapted to be mounted in said pipe line, the inner sleeve forming a continuation of the line directly exposed to fluid flowing therein and to yieldingly respond to sudden surges of pressure therein, the mean pressure in the pipe being subject to gradual variations, a perforated concentric mandrel having a plurality of throttling orifices interposed between said sleeves and isolated from the pipe fluid, cushioning compartment means encircling said con-

centric sleeves for exposing the exterior thereof to gas under substantially the mean pipe pressure to dampen such pressure surges, a source of gas under pressure, a fluid pressure reservoir for dampening abrupt variations in fluid pressure signals received thereby while responding with damped fluid pressure signals to significant changes in mean fluid pressure in the signals received, means sensing pressure changes in said pipe line and imparting a fluid pressure signal to said reservoir in response to changes in the pipe line pressure, and a control valve interconnecting said cushioning compartment and said source of gas under pressure, said control valve being

actuated in response to damped fluid pressure signals received from said reservoir.
